UNITED STATES PATENT OFFICE

2,603,976

WRENCH

John H. Hilton, North Platte, Nebr.; Albert H. Hilton, executor of said John H. Hilton, deceased

Application July 12, 1949, Serial No. 104,299

2 Claims. (Cl. 74—157)

1

This invention relates to an improved wrench, the primary object of the invention being to provide a wrench involving a longitudinally elongated handle terminating at one end in a transverse-axis work engaging element arranged to be rotated to turn the work either through swinging the handle on the axis of the work engaging element or through axial rotation of a portion of the handle which is operatively connected to the work engaging element.

Another important object of the invention is the provision of a wrench of the character indicated above wherein ratchet means is incorporated in such a way as to be operative whether the work engaging element be rotated in engagement with the work by swinging the handle or by axially rotating a part of the handle.

Other important objects and advantageous features of the invention will be apparent from the following description and appended drawings, wherein, merely for illustrative purposes, specific embodiments of the invention are set forth in detail.

In the drawings:

Figure 1 is a front end elevation.

Figure 2 is a rear end elevation.

Figure 3 is a vertical longitudinal section taken on the line 3—3 of Figure 1.

Figures 4, 5 and 6 are enlarged transverse vertical sections taken on the lines 4—4, 5—5 and 6—6 of Figure 3.

Figure 7 is a further enlarged fragmentary sectional detail taken on the line 7—7 of Figure 2.

Figure 8 is a fragmentary view similar to Figure 3 of another embodiment of the invention.

Figures 9 and 10 are transverse vertical sections taken on the lines 9—9 and 10—10 of Figure 8.

Referring in detail to the drawings, and first to Figures 1 to 7 therethrough, the embodiment of the invention therein shown comprises an axially elongated cylindrical tubular handle 12 terminating at its forward end in a laterally projecting worm-wheel case 13 of three-quarter flat cylindrical form. As indicated in Figure 4, the inner faces of the sidewalls of the case 13 are cylindrically recessed at 14, 14 to provide bearings for the pintles 15, 15 on the opposite sides of a wormwheel 16 having an axial stubshaft 17 provided with a snap detent 18 for operatively supporting a work engaging element, such as a rat socket (not shown) the stubshaft 17 projecting freely through a hole 19 provided in the adjacent sidewall of the case 13.

The inward side of the case 13 opens at 20 into

2

the adjacent side of an enlarged bore portion 21 of the handle 12, the forward end of the enlarged bore portion 21 being threaded at 22 to receive a retaining rat 23 having a tubular shank 24. The rear end of the bore portion 21 is reduced to define a shoulder 25.

A worm 26 positioned in the bore portion 21 in mesh with the wormwheel 16 terminates at its forward end in a collar 27 bearing against the rearward end of the nut shank 24 and a smooth portion 28 beyond the collar which turns in a circle of needle bearings 29 confined in the tubular nut shank 24. The rearward end of the worm 26 terminates in a collar 30 bearing against the forward end of a second circle of needle bearings 31 confined in a handle bore portion 32; and terminates in a cylindrical shaft 33 journaled in the needle bearings 31 and extending to the rearward end of the handle 12.

20 A ratchet wheel 34 larger than the handle 12 is suitably secured as indicated at 35 to the rear end of the worm shaft 33. The projecting margin of the ratchet wheel 34 retains on the handle 12 a rotary tubular hand grip 36 which tapers toward its forward end. The rear end of the hand grip 36 is axially secured to provide a ratchet chamber 37, closed by a removable cover plate 38 secured in place by screws 39. The cover plate has a concentric arcuate slot 40 through which extends a shank 41 having an annular enlargement 41' to bear against the forward side of the plate 38 in opposition to the head 42 of a screw 43 threaded into the shank 41 to clamp the shank 41 at a desired place along the slot 40.

As shown in Figures 6 and 7, the forward end of the shank 41 has diametrically opposed radially projecting arms or fingers 44, 44 which terminate at their outward ends in cylindrical bosses 45, 45 arranged to rollably bear against concavely curved surfaces 46, 46 on the outer sides of the arms 47, 47 of L-shaped ratchet dogs 48, 48 which are pivotally mounted on the plate 38 at 49, 49 equidistantly along one index of the ratchet wheel 34, with the free ends of their arms 50, 50 normally engaged with the teeth of the ratchet wheel 34 by springs 51, 51 mounted on the pivots 49 and bearing against the outer sides of the arms 50, 50. The ratchet adjusting shank 41 is shown in Figure 6 in an intermediate position wherein both ratchet dogs 48 engage the ratchet wheel 34. When the clamping screw 43 is loosened and the shank shifted along the slot 40 and clamped in a position at either end of the slot 40, the boss 45 of one shank arm 44 will have moved along the curved surface 46 of one of the

ratchet dogs 48 to the outer end of the arm 47 thereof so that the ratchet dog is held out of engagement with the ratchet wheel 34. The other ratchet dog is free and is pressed by its spring 51 into engagement with the ratchet wheel by reason of the fact that the adjustment of the shank 41 away from intermediate position withdraws the boss 45 of the related shank arm 44 from the outer end of the dog arm 47 and places it near the inner end of the arm 47 of the ratchet dog. In this arrangement of the adjusting shank 41 the shaft 33, and hence the worm wheel 16, are ratcheted to turn in one direction. With the adjusting shank positioned at the other end of the slot 40 the shaft 33 and wormwheel are ratcheted to turn in the opposite direction.

Because of the described arrangement and construction of the ratchet mechanism the wrench can be used to turn a nut or the like in a confined or difficult to reach place by applying the socket in the stubshaft 17 to the nut and rotating the hand grip 36 on the handle 12 in the proper direction to bring the nut up swung. In this action the ratchet mechanism acts to prevent retrograde or reverse rotation of the hand grip and of the nut being tightened. The nut may then be given a final tightening by swinging the handle 12 on the axis of the wormwheel 16. In this action the ratchet mechanism also acts to prevent retrograde or reverse rotation of the nut being tightened and provides step by step tightening of the nut by swinging the handle 12 back and forth.

The embodiment of the invention shown in Figures 8 to 10 is similar to that described above except that means is provided for positively locking the handgrip 36a against rotation on the handle 12a in either direction, this means taking the form of a hexagonal or octagonal portion 60 on the handle 12a at the forward end of the handgrip having slidably thereon a hexagonal or octagonal slip nut 61 arranged to enter a conformably shaped recess 62 in the forward end of the handgrip 36a, wherein the handle portion 60 is provided with a snap detent 63 for holding the slip rat releasable in place in the recess 62. The slip nut 61 is adapted to be moved out of the recess 62 when the wrench is to be operated by rotating the handgrip 36a and entered in the recess when the wrench is to be swung on the axis 50 of the wormwheel 16.

What is claimed is:

1. A wrench comprising a tubular cylindrical handle terminating at its forward end in a laterally projecting case, a wormwheel journalled in said case with its axis at right angles to the axis of said handle, a stubshaft on said wormwheel projecting axially out of said case, a shaft positioned longitudinally of and within said tubular handle and having a pair of spaced collars inwardly of and adjacent the forward end thereof journalled in said handle, a longitudinally extending worm on the portion of said shaft intermediate said collars and in mesh with said wormwheel, a ratchet wheel fixed on the rear end of said shaft and bearing against the rear end of said handle, a hollow tubular open ended hand grip journalled longitudinally on said handle and hav-

ing the rear open end extending beyond and enclosing the rear end of said handle, a cap closing and detachably secured to the rear open end of said hand grip, and reversible ratchet means on said cap operatively engageable with said ratchet wheel to operatively connect said hand grip with said shaft, said ratchet means permitting rotation of said hand grip in one direction relative to said shaft while preventing rotation of said hand grip relative to said shaft in the opposite direction, said ratchet means being arranged to prevent rotation of said hand grip relative to said shaft in said one direction while said handle is swung on the axis of said wormwheel to tighten or loosen a nut with which said stubshaft is non-rotatably connected, and means non-rotatably mounted on said handle and movable along said handle to engage a part of said hand grip for positively locking said hand grip against rotation relative to said handle.

2. A wrench comprising a tubular cylindrical handle terminating at its forward end in a laterally projecting case, a wormwheel journalled in said case with its axis at right angles to the axis of said handle, a stubshaft on said wormwheel projecting axially out of said case, a shaft positioned longitudinally of and within said tubular handle and having a pair of spaced collars inwardly of and adjacent the forward end thereof journalled in said handle, a longitudinally extending worm on the portion of said shaft intermediate said collars and in mesh with said wormwheel, a ratchet wheel fixed on the rear end of said shaft and bearing against the rear end of said handle, a hollow tubular open ended hand grip journalled longitudinally on said handle and having the rear open end extending beyond and closing the rear end of said handle, a cap closing and detachably secured to the rear open end of said hand grip, and reversible ratchet means on said cap operatively engageable with said ratchet wheel to operatively connect said hand grip with said shaft, said handle having a non-cylindrical portion in front of said hand grip, a slip nut slidably mounted on said portion and normally occupying a position forward of said handgrip, said handgrip having a part on its forward end with which said slip nut is non-rotatably engageable when moved rearwardly along said non-cylindrical portion whereby said handgrip is positively locked against rotation relative to said handle.
